[57] CLAIM

The ornamental design for a candle holder w/changeable translucent glass plates, as shown and described.

DESCRIPTION

FIG. 1 is an upper, left, front perspective view at a reduced scale of a candle holder w/changeable translucent glass plates showing my new design;

FIG. 2 is an exploded perspective view at a reduced scale; FIG. 3 is an upper, right, rear perspective view at a reduced scale;

FIG. 4 is a front elevational view;

FIG. 5 is a right side elevational view, the left side is a mirror image thereof;

FIG. 6 is a rear elevational view;

FIG. 7 is a top plan view; and,

FIG. 8 is a bottom plan view.

The broken line showing in FIGS. 1 and 2 is for illustrative purposes only and forms no part of the claimed design.
